UNITED STATES PATENT OFFICE.

CHARLES C. CUSHMAN, OF AUBURN, MAINE.

OIL BURNER.

Application filed February 19, 1925. Serial No. 10,178.

To all whom it may concern:

Be it known that I, CHARLES C. CUSHMAN, a citizen of the United States, residing at Auburn, county of Androscoggin, State of Maine, have invented certain new and useful Improvements in Oil Burners, of which the following is a specification.

The substitution of liquid fuel for hard fuel for combustion in heating, involves many and varied factors, as the prior art well illustrates. My present invention approaches the problem from a conception of fundamental simplicity. The earliest and simplest forms of burners were of the bowl type. Such a burner has many advantages, but there has grown up an astonishing multitude of complications and difficulties in its actual use.

Inadequate combustion, with all the undesirable resultants thereof, has been an insuperable deterrent to the employment of such an otherwise promising system.

In my invention, it would seem at first that I have reverted to earlier types, but through my invention I have produced results entirely novel and, therefore, present my invention as one novel and distinctive.

Without preliminary discussion of details I will proceed to a disclosure of an apparatus illustrative of my invention, and showing both principle and practical usage. The accompanying drawings are generally illustrative of my invention, but I have shown therein various features of important detail. In these drawings:

Fig. 1 is a general view of an installation in accordance with my invention.

Fig. 2 is an elevation of the fire pot unit.

Fig. 3 is a vertical section of the same.

Fig. 4 is a transverse section on line 4—4,

Fig. 5.

Fig. 5 is a plan view of the fire box equipment.

Fig. 6 is a side elevation thereof.

Fig. 7 is a section on the line 7—7 of Fig. 6, and

Fig. 8 is a sectional view of one of my vaporizing nozzles.

In dealing with my apparatus, we may consider as a common condition, the presence of a domestic heater of steam, hot water or

hot air type and having a fire box or ash chamber with a more or less standard door of rectangular form.

While various domestic heaters vary considerably in style, form and dimension, the fire door is usually more or less standard. I am, therefore, able to provide a single simple unit adapted or readily adaptable to the average heater.

As shown, it may comprise but a draft chamber 1 provided at its outer end with a flanged shield 1' which may be fitted to block the usual fire door through which the apparatus is projected into the heater. The chamber 1 may be formed with a receptacle 2 where water is to be kept in moistening relation to the draft, and is preferably disposed between the forward end of the chamber and the bowl or burner 3, which is disposed at the rear of the chamber.

The burner 3 is preferably of general cylindrical shape, having an open top and a plurality of radial, upwardly-inclined intake ports 31, above which the wall of the burner is pierced by a series of auxiliary intake openings 32. The ports 31 deliver air centrally of the burner, while the ports 32 provide a peripheral draft, thereby giving more perfect combustion.

Into the side of the bowl, preferably at about the zone of the air ports 31, is a nozzle 4 preferably of cast iron, and formed with small fins 4' and with a coupling member 4''. My supply pipe 5 connects directly to this nozzle 4 and is controlled by a valve 6. I preferably also provide an overflow outlet 7, from which a pipe 8 leads to any desired shut-off apparatus, so that in case the burner is extinguished, the flow through the feed pipe 5 will be checked.

My burner nozzles 4 may be adjustably mounted as with a cylindrical bearing 4', so it can be projected within the bowl 3 for a predetermined distance, according to the type of fuel to be burned. With the heavier fuels, the nozzle 4 extends well across the bowl, whereas with the lighter fuels, it only enters the bowl for a short distance. With such a type of burner I am able to secure an entirely satisfactory combustion of any of the ordinary fuel oils and to maintain

such combustion in suitable working relation to any ordinary type of heater.

I find it of great importance to provide certain regulation in order to get the highest perfection of results with such a simple burner. My chamber 1 gives me a body of pre-heated air on which the burner can draw. To better control the air supply of the chamber 1, I provide a draft door 9 preferably hinged at its top and balanced by a weight W. This door leads directly into the chamber 1 and is slotted to permit the passage of the pipes 5 and 8. It, therefore, permits air to enter the chamber 1, where it is warmed, and if the water tank 2 is filled, is also moistened ready to be drawn into the bowl 3.

As before described, an air supply is drawn from the chamber 1 in through the intakes 31, where it provides the necessary oxygen for the flame adjacent the center thereof. Another portion of the air passes through the holes 32 to give additional oxygen to the body of the flame just below the lip of the bowl.

The bowl is primed in the usual manner by a little kerosene, whereupon the nozzle 4 is heated so that almost immediately after the fuel is admitted through the pipe 5 it begins to gasify and be projected into the bowl is such a state.

My draft door 9 as before described, being balanced tends to close with the draft of the chamber 1 according to the demands of the burner, and the cooperating factor of the flue draft. The supply pipe 5 is provided with a control valve 6 having an arm 6¹ connecting with one branch of the chain C¹, of a chain C. The other branch C² is connected with the draft door 9 so that the draft door and valve operate simultaneously to give an increase in air supply as the fuel supply is increased. This not only keeps a proper balance and proportion between the flame and the air supply so that a clean hot flame is produced, but it prevents any possibility of the extinguishment of the flame by over draft when the fuel is cut low. A hand lever C² is also provided where it is desired to regulate the burner by manual control.

The chain C may be operated by any suitable type of thermostatic control which it is not necessary to show, and the overflow 8 may have any desired type of shut off which it is also unnecessary to illustrate.

My chamber 1 may be of any light and inexpensive material such as sheet iron and the flange 1¹ is preferably of such material so that it can be readily trimmed to fit the size of the fire door of the heater to which it is to be applied. For this purpose, the shield 1¹ is deliberately made oversize so as to accommodate the largest doors whether

they be fire doors or ash pit doors. In fact, my installation is preferably made in the ash pit and the ordinary grate of the furnace is removed so that my chamber 1 becomes a part of the heater after it is installed therein. The fire pot 31 is preferably a casting and together with its nozzle 4 builds up or accumulates heat, thus keeping uniform the volatilization of the fuel.

My apparatus may be variously designed for combination with various types of heaters, but the form shown is adapted to almost all ordinary types of heaters and has many advantages in the simplicity of its construction.

What I therefore claim and desire to secure by Letters Patent is:

1. In combination with a domestic heater, an intake chamber projected within the fire door of the heater and having a draft door, a burner bowl set in said chamber and projecting through the top thereof and having lateral intake draft pipes leading from the chamber to within the walls of the bowl to supply air centrally of the burner, said bowl wall having a plurality of smaller draft openings above said draft pipes for supplying air and adjacent the lip thereof, and a fuel nozzle radially of the bowl and projecting between the draft pipes.

2. In combination with a domestic heater, an intake chamber projected within the fire door of the heater and having a draft door, a burner bowl set in said chamber and projecting through the top thereof and having lateral intake draft pipes leading from the chamber to within the walls of the bowl to supply air centrally of the burner, and a fuel nozzle radially of the bowl and projecting between the draft pipes.

3. In an oil burning apparatus for domestic heaters, an intake chamber projected within the fire door of the heater and having a gravity controlled draft door for said chamber, a burner bowl set in said chamber and projecting through the top thereof and having lateral upwardly inclined intake draft pipes leading from the chamber to within the walls of the bowl to supply air centrally of the burner, said bowl wall having a plurality of smaller draft openings above said draft pipes for supplying air peripherally of the bowl and adjacent the lip thereof, and a fuel nozzle adjustable radially of the bowl and projecting between the draft pipes.

4. In an oil burning apparatus for domestic heaters, an intake chamber projected within the fire door of the heater and having a gravity controlled draft door for said chamber, a burner bowl set in said chamber and projecting through the top thereof, draft pipes leading from said intake chamber into said bowl, a fuel nozzle adjustable radially of the bowl and projecting between the draft pipes.

ally of the bowl and projecting between the draft pipes, and a fuel supply connected with said nozzle.

5. In an oil burning apparatus for domestic heaters, a burner bowl having lateral intake draft pipes leading from the chamber to within the walls of the bowl to supply air centrally of the burner, said bowl wall

having a plurality of smaller draft openings above said draft pipes for supplying 10 air peripherally of the bowl and adjacent the lip thereof, a fuel nozzle radially of the bowl and projecting between the draft pipes.

In testimony whereof I affix my signature.

CHARLES C. CUSHMAN.
